UNITED STATES PATENT OFFICE.

ANNA K. MAY, OF PHILADELPHIA, PENNSYLVANIA, ASSIGNOR TO MCCALLUM & MCCALLUM, OF SAME PLACE.

DESIGN FOR CARPET.

SPECIFICATION forming part of Design No. 26,536, dated January 12, 1897.

Application filed December 4, 1896. Serial No. 814,446. Term of patent 33 years.

To all whom it may concern:

Be it known that I, ANNA K. MAY, a citizen of the United States, residing at the city of Philadelphia, in the county of Philadelphia and State of Pennsylvania, have invented and produced a new and original Design for a Carpet or other Fabric, of which the following is a specification, reference being had more particularly to the accompanying drawing, illustrating the same and forming part hereof.

The leading feature of my design is a chintz pattern of anchors emblazoned with conventionalized fish forms.

In the drawing, *a* is the body, *b* the border, and *a b* the complete carpet. *c* are anchors, and *d* are conventionalized fish forms arranged in a chintz pattern, as shown. *e* are spots or links intended to obviate a striped appearance. *f* are festoons, and *g* are bands of cables and links. *i* are lattice-like stripes.

The design of my invention will be best understood by reference to the drawing, and it may be expressed in any desired colors or combinations of colors and applied to velvet, 25 Wilton, Brussels, or other carpeting.

What I claim as my invention, and desire to secure by Letters Patent, is—

1. In a design for a carpet the body *a*, substantially as shown and described. 30
2. In a design for a carpet the border *b*, substantially as shown and described.
3. The design for a carpet consisting of the body *a*, and border *b*, substantially as shown.

In testimony whereof I have hereunto signed my name.

ANNA K. MAY.
